Primary Examiner—Charles A Rademaker*(74) Attorney, Agent, or Firm*—Cesari and McKenna, LLP(57) **CLAIM**

The ornamental design for a medical implant, as shown and described.

DESCRIPTION

FIG. 1 a perspective view of a medical implant according to my new design;

FIG. 2 is a front elevational view thereof;

FIG. 3 is a rear elevational view thereof;

FIG. 4 is a right side elevational view thereof, the opposite side being a mirror image;

FIG. 5 is a top plan view thereof; and,

FIG. 6 is a bottom plan view thereof.

The broken lines shown in FIG. 1 form no part of the design and are for illustrative purposes only.
